[57] CLAIM

The ornamental design for a pocket for a golf scorecard and accessories, as shown and described.

DESCRIPTION

FIG. 1 is a perspective view of a pocket for a golf scorecard and accessories showing my new design, the broken lines showing a garment and golf accessories being for illustrative purposes only and forming no part of the claimed design;

FIG. 2 is an enlarged left side elevational view thereof;

FIG. 3 is a right side elevational view of FIG. 2;

FIG. 4 is a rear elevational view of FIG. 1; and,

FIG. 5 is a top view of the pocket of FIG. 1.
The broken lines shown in FIGS. 1 through 4 on the claimed article are understood to represent conventional stitching.

FIG. 2

FIG. 5
